UNITED STATES PATENT OFFICE.

TIMOTHY AUGUSTINE COGHLAN, OF LONDON, ENGLAND.

TREATMENT OF WOOL TO PREPARE IT FOR MANUFACTURE.

Application filed July 7, 1921. Serial No. 482,949.

To all whom it may concern:

Be it known that I, TIMOTHY AUGUSTINE COGHLAN, a subject of the King of Great Britain, residing in London, England, have 5 invented a certain new and useful Improved Treatment of Wool to Prepare It for Manufacture, of which the following is a specification.

Certain advantages presented by the use 10 of trichlorethylene for extracting wool grease from wool, are known. I have discovered another, namely that the condition of the wool which has been treated with this solvent is such that when it is desirable that 15 the wool should be treated by non-mechanical means for the removal of burrs or other vegetable matter embedded in the wool, the staple remains unaffected by the application of sulphuric acid, otherwise known as car- 20 bonising.

The objection which has hitherto militated against the use of trichlorethylene has been the difficulty of recovering the solvent left in the wool, such recovery being 25 essential both for preventing injury to the workmen and for the economy of the process. Attempts to expel the solvent by means of hot air have not been successful, partly because of the tendency of air in the 30 presence of moisture, which cannot well be excluded, to oxidise trichlorethylene with formation of hydrochloric acid, and partly because of the difficulty of condensing vapour of trichlorethylene when carried by a 35 large volume of air. Steam has been suggested as a substitute for air but it is known to be inadvisable to expose wool to a higher temperature than 45° C.

By my invention the trichlorethylene is 40 expelled from the wool at a temperature of 45° C. or lower, by water, which has the advantage that the wool is simultaneously washed, or by carbon dioxide from which, I find, it is far easier to condense tri- 45 chlorethylene vapour than it is to condense that vapour from air; as it is easy to obtain carbon dioxide substantially free from air the trouble of possible oxidation disappears.

Commercial trichlorethylene of boiling 50 point about 90° C. may be used. The action of the reagent on metals and on lubricants is such that certain precautions in the construction and arrangement of apparatus 55 are necessary. For instance, its action on lead is such that this metal must be avoided

or in some way protected, lest the colour of the wool be affected. Again, where packed joints are required, greasy fabric and lead should preferably be avoided; or the action 60 may be prevented by the interposition of an absorbent, for instance, between the vessel in which the vapour of the reagent is being generated and the exhauster, or the like.

A considerable economy is attained by the 65 successive treatment of the wool in trichlorethylene that has already been used, as this substance when warmed to say 40° C. will take up three or more times its volume in wool grease, but the final operation 70 should be done with clean trichlorethylene.

In one form of the process the wool to be treated either in its original condition or more or less opened up, is charged into a cage which is run on wheels or slid into a vessel, preferably a cylinder having its axis horizontal and one end formed as a door which can be hermetically sealed. Otherwise the cage may be lowered into the treatment vessel from above, in which case 75 the top or open side should be appropriately faced to form an hermetic closure with a lift-away or hinged cover having means for fastening it when closed. This vessel having been evacuated of air as far as practicable, trichlorethylene is run into it and is heated in the vessel by steam coils or the like to a temperature of about 45° C. The reagent first applied to the raw wool may have been used several times. For the sake 80 of illustration it is assumed that the trichlorethylene has been used twice. After remaining in the chamber for a period of fifteen (15) minutes less or more according to the condition of the wool, the trichlor- 85 ethylene is run into a storage tank for thrice used liquid, or directly into a still, for the recovery of the reagent and the grease. Its place in the vessel is now taken by trichlor- 90 ethylene which has been used once before, which is heated to the said temperature and then run into the storage tank for twice used liquid, its heat being retained as far as possible in any suitable manner. Finally, 95 unused trichlorethylene is admitted to the vessel and after having been heated to the said temperature, is run into the once used liquid storage tank, with retention of its heat.

In order to make the operation more 110 continuous, two or more vessels may be used, the solvent from one being run into a

second and so on, in order that there may always be a vessel being discharged and another being charged.

In another form where large quantities of wool have to be treated the trichlor-ethylene is introduced into the first of a series of connected vessels charged with wool which have been evacuated of air as far as practicable, and after standing a short time is allowed to enter a second chamber, preferably at the bottom, and to pass out of that chamber into the third chamber, and so on until it passes through the whole series of chambers entering each at the bottom and being drawn off at the top. When the wool in the first chamber has been deprived of its grease, or is considered to be sufficiently treated, that chamber is disconnected from the flow of trichlorethylene and the wool in the vessel dealt with as hereinafter described.

When the wool has been removed the vessel is again charged, evacuated of air to the required extent and connected with the last vessel of the series. After the first vessel has been disconnected, further trichlorethylene is admitted to the second vessel passing through the whole series as before. When the wool in the second vessel has been sufficiently treated the flow to that vessel is shut off and the same course followed as in the case of the first vessel. Each vessel is dealt with in turn so that the final treatment of the wool is made with unused trichlorethylene. When every vessel of the series has been dealt with, or whenever convenient, the used trichlor-ethylene will be passed through a still and condenser, for the recovery of the reagent from the grease. The recovered trichlor-ethylene will be collected in a storage tank suitably placed.

In ordinary use each vessel would contain the quantity of greasy wool in an ordinary bale, about 380 lbs. When different classes of wool are being treated and it is not desirable to mix them, smaller vessels may be used; but for general purposes, the economic size of a vessel would be to contain 380 to 440 lbs.

This system is illustrated in the accompanying diagram Fig. 1 which shows the state of affairs when the second vessel in the series has become the first to receive fresh solvent.

1, 2, 3, 4 represent the vessels (there may be a much larger number) each nearly filled with wool and all connected through respective valves *a* with the vacuum pump attached to pipe *e*. Valve *d* is in the position for flow of solvent from overhead tank *f* to pipe *g*, and valve *c'* is open to admit solvent into the vessel 2. After the necessary sojourn (about fifteen minutes) of the solvent in vessel 2, valve *c'* is closed and

valve *b'* is turned into the position shown, there being a vacuum in vessel 3 and pipe *h* extending to the bottom of vessel 2, the pressure of the vapour of solvent in vessel 2 forces the solvent through pipe *h* in vessel 70 3. This process is repeated in the succeeding vessels until the series is completed or until the solvent is sufficiently saturated with grease. In the meantime vessel 1 has been recharged with wool and evacuated, 75 so that when valve *b'* has been turned into the position shown and valve *d* into the position for connecting pipes *k* and *l*, the solvent flows as before from vessel 4 to vessel 1, now the last in the series. From here it may 80 be re-circulated through the system, but generally it is sufficiently saturated with grease; valve *b'* is therefore turned into the position shown so that the solvent may flow as before through pipe *m* into the storage tank or 85 still *n* which may be connected with the vacuum pump through a suitable pipe not shown in Fig. 1. From the pipe connections indicated it will be seen that each vessel is capable of being the first or the last to 90 receive solvent as the case may be. The functions of valves *b'*, *c'*, *c'* will be apparent from the above description.

Fig. 2 shows an elevation and Fig. 3 a plan of a plant constructed to operate on this 95 system.

The vessels 1, 2, 3, 4 are adapted to receive the wheeled cages containing the wool which run on rails *o*. Each vessel is adapted to be heated by an internal steam coil. 100 The vacuum pump *p* serves both for exhausting the vessels through pipes *q* and *e* and for distilling the spent solvent in the still *n*. *r* is a distillation column, *s* a condenser, *t* a receiver for the trichlorethylene and *u* 105 a pump for raising the latter to the overhead tank *f*. The parts marked with the same letters as those used with reference to Fig. 1 have the functions already explained.

The residual trichlorethylene contained in 110 the treated wool may be recovered before the wool is removed either by the use of hot water or of carbon dioxide. In the first case hot water is run into the vessel, a temperature of about 45° C. being maintained 115 under a partial vacuum while the vessel is open to a condenser whereby the residual reagent is recovered. Afterwards this water is run off, preferably through a heat inter-changer, and is either worked up for potash 120 salts or run to waste.

Instead of hot water the treated wool may be subjected to a current of carbon dioxide which may be preheated to such temperature as may be necessary, but always so that 125 the temperature of the wool does not exceed 45° C. The current becomes saturated with trichlorethylene vapours; it thence is passed through a condenser, properly cooled and made to bubble through oil in a suit- 130

ably arranged tank; the trichlorethylene will be absorbed by the oil while the carbon dioxide goes to the gas holder from which it reverts to the process. This system of treatment by carbon dioxide is valuable in places where the use of water is not desired; if water is available, hot water may be run into the vessel for the purpose of carrying off the potash salts held by the wool. Afterwards, this water is run off preferably through a heat interchanger and worked up for potash salts, should that be considered desirable.

The wool, after being removed from the chamber, will be practically free from grease and potash salts, nevertheless, it may with advantage be washed or rinsed in clean water to free it from sand or other mineral substances held loose in the wool now that the grease has been removed, but any vegetable substance will still remain. The wool may now be dried by any of the known methods, after which it will be ready to undergo treatment to prepare it for the processes of manufacture, and will be in

the condition indicated in paragraph 3 hereof. If recourse is necessary to carbonising, it will be found that the treatment of wool according to this process enables the fibre to withstand the action of sulphuric acid without the loss sustained under all of the processes of preparation now in practical use.

Having thus described the nature of the said invention and the best means I know of carrying the same into practical effect, I claim:—

A process of preparing wool for manufacture, which consists in charging the wool into a series of connected vessels, then successively charging each vessel with trichlorethylene and discharging the trichlorethylene, then charging each vessel with carbon dioxide at a temperature not exceeding 45° C. and collecting and condensing the trichlorethylene thus expelled from the wool.

In testimony whereof I have signed my name to this specification.

TIMOTHY AUGUSTINE COGHLAN.
